UNITED STATES PATENT OFFICE.

ALFRED WILLIAM SOUTHEY, OF LONDON, ENGLAND, ASSIGNOR TO SOUTHEY GAS PRODUCERS LIMITED, OF LONDON, ENGLAND.

PRODUCTION OF GASEOUS FUEL FOR INTERNAL-COMBUSTION ENGINES.

1,351,193.

Specification of Letters Patent. Patented Aug. 31, 1920.

Application filed August 16, 1916. Serial No. 115,199.

To all whom it may concern:

Be it known that I, ALFRED WILLIAM SOUTHEY, a subject of the King of Great Britain, and resident of 38 Hale Lane, Mill Hill, London, England, engineer, have invented new and useful Improvements in the Production of Gaseous Fuel for Internal-Combustion Engines, of which the following is a specification.

10 Among the methods which have been proposed for the production of gaseous fuel for internal combustion engines from liquid hydrocarbons, such for example as paraffin, there is one which by the partial combustion 15 of the liquid fuel produces a mixture formed partly of combustion products and partly of unburnt fuel in a gaseous condition.

If a mixture of this description is led to the cylinders of an internal combustion engine 20 it is sometimes found to be a fuel deficient in power owing to loss of calorific value due to increased intensity of the flame and sometimes when the intensity of the flame is less by reason of a limitation of the 25 supply of air the fuel is insufficiently vaporized and there is condensation in the cylinders and a dirty exhaust.

To obtain satisfactory results it is necessary to properly vaporize the liquid fuel 30 and to superheat the vapor and to do this without wasting the calorific value of the fuel.

According to the present invention I do not as in some previous methods, inject 35 liquid fuel into a flame and allow combustion of the said fuel to take place in the presence of air a sufficiency of which at all times cannot be determined but I cause a high temperature flame to which air has been freely 40 supplied so as to insure that the flame consequent on the condition of complete combustion is drawn by the suction of the engine in the direction of the cylinders and comes into direct contact on its way with 45 liquid fuel which is also drawn into a space where the flame is quenched by the fuel so that no further combustion takes place by reason of the absence of air to support it. A superheated vapor is thus produced which 50 with air added later constitutes a highly satisfactory gaseous fuel for internal combustion engines.

The suction of the engine which is variable regulates the intensity of the flame and takes

no more fuel than the flame is able to gasify 55 and superheat; there is therefore an automatic adjustment of fuel to flame without destruction of the calorific value of the former.

In the accompanying drawing I have illustrated diagrammatically two forms of apparatus by which my invention may be carried into effect.

Figures 1 and 2 are both sectional elevations. 65

Fig. 3 is a sectional elevation of a practical apparatus embodying my invention.

Referring to Fig. 1 *a* is a kind of double pan with a compartment *b* for the wicks *c*. *d* is an upstanding tube of suitable sectional area and *e* is a chamber having an orifice *e*¹ open to and situated above the end of the tube *d*. The chamber *e* has at its opposite end an outlet *f* leading to the engine cylinders. Liquid fuel is contained within the space *g* formed by the double bottom of the pan, within the wick chamber *b* and within the tube *d* and the level of the liquid is maintained constant at approximately the height of the tube *d* by any convenient form of float. The space *h* surrounding the tube *d* is 70 empty of fuel and open to the air. 75

The flame from the wicks is drawn by the suction of the engine into the orifice *e*¹ of the chamber *e* around the tube *d*. Here the flame 80 meets the liquid fuel which is delivered from the tube *d* and vaporizes it in accordance with the intensity which the flame possesses and which is determined by the draft created by the suction of the engine. Sufficient air 85 is not admitted to the chamber *e* to support combustion and consequently the flame is quenched by the fuel at the orifice *e*¹ and no further combustion takes place. There is 90 therefore no destruction of the calorific value of the fuel which is merely vaporized and superheated. If air were admitted to the chamber *e* the interior of the latter would be full of flame and the calorific value 95 of the vaporized fuel would be destroyed. 100

The apparatus shown in Fig. 2 acts in a similar manner but in this case the bottom of the chamber *e* is open to the trough *g* containing the liquid fuel and the flame from the wicks is drawn into the said chamber by a depending pipe *d*¹ so that the flame impinges upon the surface of the fuel, maintained constantly on a level with the end of 105

the pipe d^1 , and carries away a superheated and unburnt vapor suitable for firing an engine.

I may remark that the apparatus employed for carrying out my invention is capable of considerable variation and will be constructed in accordance with the character of the liquid fuel employed and other circumstances. As above indicated the forms of apparatus herein described and illustrated in Figs. 1 and 2 are only intended to be diagrammatic.

I will now describe the practical form of apparatus shown in Fig. 3.

15 a is a tank containing a space b for the wicks c and surrounding the space b , an annular trough g for the float i . Fuel enters the trough g by the orifice j which is furnished with a valve k operated by the float i 20 through the pivoted lever l . The fuel flows into the wick space b by holes m . Within the space b is an empty receptacle h open at the top. d is a tube or nozzle for the fuel the end of which nozzle extends somewhat 25 above the level of the fuel in the surrounding spaces b and g indicated by the broken line. The fuel is admitted to the nozzle d by the holes n and the chamber o the latter being formed by a tubular portion depend- 30 ing from the bottom of the receptacle h and constituting a support for the latter within the space b . p is a screw plug for closing the bottom end of the chamber o and q is a strainer for the fuel at the bottom of the 35 nozzle d . r is a cover for the trough g . s is a place for a sparking plug therein and t is a covered aperture for lighting the wicks when required.

Surrounding the upper portion of the 40 nozzle d is the orifice e^1 of the chamber e which opens at its upper end into the mixing throttle u which it is not necessary here to describe.

It will be seen that the chamber e is supported by an external annular portion v 45 resting on an upstanding ring w which forms part of the cover r before mentioned. x are flap valves in the portion v for admitting air freely into the space b and for enabling the fuel to burn at the wicks c . The 50 flame from the wicks is drawn by the suction of the engine in the direction of the arrows into the orifice e^1 where it meets the fuel from the tube d as in the manner explained with reference to the diagrams Figs. 55 1 and 2.

No claim is herein made to the novel features of the above described practical form 60 of apparatus for carrying out the improved method as the same constitute the subject matter of an application filed March 14, 1917, Serial No. 154,832.

What I claim and desire to secure by Letters Patent of the United States is:—

65 1. The method herein described of mak-

ing gaseous products which consists in producing a flame, conducting said flame into a restricted passage so as to reduce the cross sectional area of the flame and thus obtain a zone of high temperature, and subjecting 70 liquid fuel to the flame at said restricted zone of high temperature.

2. The herein-described method of making gaseous products, which consists in producing a flame, conducting said flame into a 75 restricted passage, subjecting liquid fuel to said flame in said passage, and maintaining in said passage an insufficient amount of air to support combustion.

3. The herein described method of making 80 gaseous products which consists in producing a flame, sucking said flame into a restricted passage so as to obtain a zone of high temperature, and drawing by suction liquid fuel in the form of a spray into the 85 zone of high temperature and at which point there is an insufficient amount of air to support combustion of the added fuel.

4. The herein-described method of making 90 gaseous products, which consists in substantially surrounding the open end of a chamber with a flame, drawing said flame in constricted condition into said chamber, and introducing fuel into said chamber at the point of constriction of said flame. 95

5. The herein-described method of making 100 gaseous products, which consists in maintaining a substantially annular flame about the contracted end of a chamber, passing said flame into and through such contracted end to produce a zone of high temperature at such point, introducing liquid fuel in finely-divided condition into said zone, and maintaining in said zone an insufficient amount of air to support combustion. 105

6. The herein-described method of making 110 gaseous products, which consists in maintaining a substantially annular flame about the contracted end of a chamber, passing said flame into and through such contracted end to produce a zone of high temperature at such point, introducing liquid fuel in finely-divided condition into said zone, maintaining in said passage an insufficient amount of air to support combustion and expanding the resultant products into 115 said chamber.

7. The herein-described method of making 120 gaseous products, which consists in maintaining a substantially annular flame about the contracted end of a chamber, passing said flame into and through such contracted end to produce a zone of high temperature at such point, introducing liquid 125 fuel in finely-divided condition into said zone, maintaining in said zone an insufficient amount of air to support combustion, expanding the resultant products into said chamber, and adding air to said products 130

at a point sufficiently remote from said zone to prevent combustion.

8. The herein-described method of making gaseous products, which consists in maintaining a substantially annular flame about an open-ended tube, sucking said flame in constricted condition into and through said tube, drawing liquid fuel in finely-divided condition into said tube substantially centrally thereof, and maintaining in said tube an insufficient amount of air to support combustion.

9. The herein-described method of making gaseous products, which consists in producing a flame, supplying atmospheric air to said flame, constricting said flame to produce a zone of high temperature, introducing fuel to said flame at said zone, and

quenching said flame to prevent combustion of the product.

10. The herein-described method of making gaseous products, which consists in producing a flame, passing said flame through a restricted passage to produce a zone of high temperature, introducing fuel to said restricted passage in lines parallel with the line of travel of said flame, and maintaining in said passage an insufficient amount of air to support combustion.

In testimony whereof I have signed my name to this specification in the presence of two subscribing witnesses.

ALFRED WILLIAM SOUTHEY.
